(57) **CLAIM**

The ornamental design for a cover lid, as shown and described.

DESCRIPTION

FIG. 1 is a top, front, left perspective view of a cover lid showing our new design;

FIG. 2 is a top, rear, left perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof;

FIG. 8 is a bottom plan view thereof; and,

FIG. 9 is a top, front, left perspective view thereof, shown in an environment of use.

The broken lines showing a container in FIG. 9 are for the purpose of illustrating environmental structure, and form no part of the claim.
